(57) **CLAIM**

The ornamental design for a tray with indented canals, as shown and described.

DESCRIPTION

FIG. 1 shows a top and side perspective view of a tray with indented canals.

FIG. 2 shows a bottom and side perspective view thereof. FIG. 3 shows a top plan view thereof.

FIG. 4 shows a bottom plan view thereof.

FIG. 5 shows a first side view thereof, the opposite side being a mirror image thereof.

FIG. 6 shows a second side view thereof, the opposite side being a mirror image thereof; and,

FIG. 7 shows a cross section of section line 7-7 of FIG. 5. The broken lines in the drawings depict portions of the tray that form no part of the claimed design.

1 Claim, 5 Drawing Sheets(56)
